CLAIM

I claim the ornamental design to a choke collar, as shown and described.

DESCRIPTION

FIG. 1 is a first top perspective view of a choke collar of my new design shown in a first position.

FIG. 2 is a close-up, enlarged top perspective view of the choke collar in a second position.

FIG. 3 is another close-up, enlarged top perspective view of the choke collar in a third position.

FIG. 4 is a close-up, enlarged side perspective view of the choke collar in a fourth position.

FIG. 5 is another close-up, enlarged side perspective view of the choke collar in a fifth position.

FIG. 6 is another perspective view of the choke collar in an arrangement similar to FIG. 1; and,

FIG. 7 is last perspective view of the choke collar in an arrangement similar to FIG. 1.
